J. Franklin Regart

United States Patent Office.

MICHAEL SIMONS, OF MIDDLETOWN, CONNECTICUT.

Letters Patent No. 65,958, dated June 18, 1867.

IMPROVED ICE-PITCHER.

The Schedule referred to in these Letters Patent and making part of the same.

TO ALL WHOM IT MAY CONCERN:

Be it known that I, MICHAEL SIMONS, of Middletown, Middlesex county, State of Connecticut, have invented an Improved Ice-Pitcher; and I do hereby declare the following to be an exact description of the same, reference being had to the accompanying drawings, and to the letters of reference marked thereon, making a part of this specification, in which—

Figure 1 represents a vertical section of the pitcher.

Figure 2, a view of the bottom.

The nature of my invention consists in the construction of the inside bottom set up into the body of the pitcher, so as to be easily removed and repaired, or replaced by a new bottom; also, the movable outside bottom by means of a catch and clip at one side, and a pivot latch on the other side, to hold the bottom to its place, or be easily removed.

A represents the handle; B, the spout; C, the spout-valve; D, the lid; E, the pitcher or outside cylinder; F, the base; G, the lower or outside bottom, having a catch, H, and a clip, J, to fasten into. The catch H is riveted fast to the one side of the bottom, and the clip J is attached to the rim of the top edge of the base F. On the other side of the rim is a hook, into which the latch L catches, the latch L being a flat piece of metal operating on a pivot in the bottom G, so as to hold the bottom fast to its place. M is the inner cylinder of the pitcher, with an inch space between it and the outer cylinder E. The bottom P of this inner cylinder is turned up around its edge, so as to fit into the lower edge of the cylinder M, and be soldered fast to the cylinder M, so that as the inside bottom becomes worn by the ice being thrown in it can be easily repaired or replaced, and is stiffer and not so liable to be broken.

What I claim as my invention, and desire to secure by Letters Patent, is—

The inside bottom P and the outside bottom G, with its devices H and L, when arranged and constructed as herein described and for the purposes set forth.

MICHAEL SIMONS.
